UNITED STATES PATENT OFFICE

JOSEPH OWSIAK, OF NEW BRITAIN, CONNECTICUT

SHADE AND CURTAIN FIXTURE

Application filed August 7, 1929. Serial No. 384,116.

This invention relates to curtain fixtures, and has in view to provide a simple arrangement whereby a number of different forms of curtain and shade brackets may be interchangeably mounted on a window frame without the necessity of forming different fastener holes in the frame for the various different brackets.

The invention contemplates the provision of a base plate adapted to be permanently mounted on a window frame, and any desired number of different shade and curtain bracket elements adapted to be interchangeably mounted on said base plate, and in connection with this general scheme, it is a further purpose of the invention to provide a base plate and brackets of attractive design which may be produced cheaply and easily from sheet metal by a stamping operation, and to provide a simple, effective means for quickly detachably securing any particular bracket on the base plate positively in any one of a plurality of different positions.

With the foregoing and other purposes in view, the invention consists in the novel features of construction, combination and arrangement of parts as will be hereinafter more fully described, illustrated in the accompanying drawings and defined in the appended claims.

In the drawings, wherein like characters of reference denote corresponding parts in the different views:

Fig. 1 is an elevation of the upper portion of a window frame showing one manner of mounting the present fixtures on the frame thereof.

Fig. 2 is a view similar to Fig. 1 showing a narrower window and another manner of mounting the present fixtures on the frame thereof.

Fig. 3 is an enlarged front elevation illustrating one practical embodiment of a base plate with a bracket mounted thereon in accordance with the invention.

Fig. 4 is a longitudinal section on the line 4—4 of Fig. 3.

Fig. 5 is an enlarged front elevation illustrating another form in which the base plate may be produced; and

Figs. 6 to 17 are perspective views illustrating various forms of brackets adapted to be mounted on a window frame by means of either of the base plates shown in Figs. 3 and 5 of the drawings.

Referring particularly to Figs. 3 and 4 of the drawings, it will be observed that the present invention contemplates the provision of a pair of base plates A (Figs. 3 and 4) and A' (Fig. 5). The base plates A and A' are preferably stamped from sheet metal, but are capable of being produced in any other suitable or desired manner, to include essentially a generally flat, front face portion 10 and a marginal flange 11 extending rearwardly from said front face portion for engagement with a window casing 11a to maintain said front portion in spaced relation thereto.

Suitably located openings 12 are formed through the front face portion 10 of the base to accommodate suitable fasteners, such as wood screws 13, for securing the base to a window frame. In addition, the front face portion 10 is pressed outwardly to provide one or more hollow sockets 14 of any desired polygonal shape, but preferably being square as viewed from the front, and of such depth as to accommodate a sufficient portion of a nut 15 so that the latter, which more or less neatly fits within the socket 14, is held thereby against rotation.

The nuts 15 are fitted into the sockets 14 before the base plate is secured to the window frame, and thus when the base plate A is secured to the window frame, the nuts are positively retained in the sockets by means of the screws 13.

Figs. 3 and 4 of the drawings illustrate a base plate A having a plurality of sockets 14, while Fig. 5 illustrates a second form of base plate A' having only a single socket formed thereon. The particular use to which the base plates are to be put will, of course, determine the number of such sockets 14 to be provided thereon, in which connection it is manifest that the number of sockets is optional and in different base plates may be varied at will.

Each socket 14 is formed with a central

opening 16 to permit the insertion therethrough, from the front of the base, of a short cap screw 17 for engagement with the nut 15 to detachably secure a curtain or shade bracket to the base.

As illustrated in Figs. 6 to 17, various shapes and forms of brackets may be provided, each adapted for detachable interchangeable attachment to any given base 10 plate. The differences between the various brackets illustrated are believed to be apparent from the drawings and it is not believed, therefore, that additional detailed explanation of such differences is necessary.

15 It is particularly to be noted with respect to each of said brackets, however, that same is inclusive of a base 18, and that said base is pressed or otherwise formed with a pocket 19 of a size and shape to receive a socket 14 20 of a base plate A or A' etc. Thus, any bracket is adapted to be engaged in any one of a plurality of different rotated positions with any base plate.

The sockets of the base plate neatly fit into 25 the pockets of the brackets, whereby the latter will be positively held against shifting or rotating out of position. The wall constituting the outer end of each pocket 19 is aperture as at 20 for the accommodation of the 30 screw 17 previously mentioned.

As illustrated in Figs. 1 and 2, the base plates A and A' may be secured in different 35 positions on a window frame, but it will be obvious that brackets of various other desired forms may be interchangeably attached to the same base plates, whereby marring or otherwise injuring the window frame when the brackets are changed will be entirely avoided.

40 While there have been disclosed in this specification several forms in which the invention may be embodied, it is to be understood that these forms are shown for the purpose of illustration only, and that the invention 45 is not to be limited to the specific disclosures but may be modified and embodied in various other forms without departing from its spirit. In short, the invention includes all the modifications and embodiments coming 50 within the scope of the following claims.

Having thus fully described the invention, what is claimed as new, and for which it is desired to secure Letters Patent, is:

1. A curtain fixture comprising, in combination a base plate having a polygonal raised portion adapted to be permanently secured to a window frame, and a curtain bracket having a corresponding polygonal recess adapted for interfitting engagement in a plurality of 60 different angular positions with the cooperating polygonal raised portion on the base plate.

2. A curtain fixture comprising a base plate adapted to be secured permanently to a window frame, a polygonal hollow socket formed

on said base plate, a polygonal nut disposed within said socket, a bracket having a polygonal pocket adapted to receive said socket, and a screw adapted to be passed through said bracket and said socket and threaded 70 into said nut to secure said bracket to said base plate.

3. A curtain fixture comprising a base plate adapted to be secured permanently to a window frame, a polygonal nut retained between 75 said bracket and the window frame, an offset polygonal socket on the outer face of said base plate, a bracket having a polygonal pocket to receive said socket, and a screw adapted to be passed through said bracket and threaded 80 into said nut to secure the bracket to the base plate.

4. A curtain fixture comprising a base plate having a rearwardly directed marginal flange adapted to be engaged against the face of a window frame, means for securing said base plate permanently to the window frame, said base plate being formed from sheet metal 85 pressed to provide an outwardly extending polygonal hollow socket, a nut fitting within 90 said socket between the base plate and the face of the window frame, a curtain bracket having a polygonal pocket to receive said socket, and a screw adapted to be passed through said bracket and threaded into said 95 nut to detachably connect said bracket with said base.

5. A curtain fixture comprising, in combination a base plate having a square raised portion adapted to be permanently secured 100 to a window frame, and a curtain bracket having a square recess adapted for interfitting engagement in a plurality of different angular positions with the cooperating square raised portion on the base plate.

In testimony whereof, I have affixed my signature to this specification.

JOSEPH OWSIAK.
